UNITED STATES PATENT OFFICE.

ANTON GJELSTAD, OF SANDEFJORD, NORWAY.

FRAME FOR RIVETING-TOOLS.

1,295,727.

Specification of Letters Patent. Patented Feb. 25, 1919.

Application filed October 12, 1917. Serial No. 197,022.

To all whom it may concern:

Be it known that I, ANTON GJELSTAD, a subject of the King of Norway, residing at Sandefjord, in the Kingdom of Norway, have invented certain new and useful Improvements in Frames for Riveting-Tools; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to a support for pneumatic riveting hammers—and particularly for hammers for working from below for instance at the bottom of a ship.

The object of the invention is to provide 20 a support of this kind which is able to keep the hammer in position and at the same time guide it in such a manner that it moves on a conical surface thereby hammering the rivet from varying angles in succession.

25 On the drawings:

Figure 1 is a vertical section and Fig. 2 is a plan of the apparatus with the top removed.

The support comprises a tripod having 30 adjustable legs 1 on which is mounted a base plate 2 carrying a guide frame consisting of a plurality of upwardly inclined converging bars 3 connected at their upper ends by a bearing ring 3'.

35 The riveting hammer (not shown) is preferably of the pneumatic type of any suitable well-known construction, and is supported in an upright position within the guide frame, the upper portion of the hammer casing projecting loosely through the

40 ring so that the longitudinal axis of said casing is free to describe a cone, or is readily shifted from a vertical to an inclined plane, as hereinafter described.

45 A disk 6 is concentrically journaled in the base plate 2 and is rotated thereon by a crank 6' through the medium of a bevel gearing 6''. Pivotally mounted on the rotatable disk, near the periphery thereof, is

a guide piece 5, and in the top face of the latter at a point capable of intersecting the axis of the disk 6 is a recess 4, forming a seat for the base of the casing of the riveting hammer.

For the purpose of shifting the seat 4 eccentrically to the axis of the disk 6 and thereby inclining the casing of the riveting hammer, the guide piece 5 is conveniently provided with an extension or handle 7, and, in order that the guide piece may be locked with the seat in the desired position, a locking screw 8, carried by the extension, is adapted to take into any one of a series of holes formed in the disk 6 concentric to the pivot of the guide piece 5.

By adjusting the guide piece 5 by means of handle 7 and screw 8 the recess 4 will be placed in a more or less eccentric position with regard to disk 6, and will when the disk 6 is rotated, consequently move the lowest part of the hammer in a circle of a smaller or larger diameter.

The hammer itself will thereby describe a cone during the riveting operation whereby the most correct working is obtained.

I claim:

1. In a frame for riveting tools, a revolving hammer-support, means to shift the latter relatively to the axis of revolution, and means to guide the hammer whereby the longitudinal axis of the latter describes a cone.

2. In a frame for riveting tools a guide frame for the hammer, a rotatable disk, a support for the hammer carried by the disk, and means to adjust the support relatively to the axis of the disk and thereby change the inclination of the longitudinal axis of the hammer.

3. In a frame for pneumatic riveting hammers, a guide frame for the hammer, a rotating disk and an eccentrically adjustable guide piece having a seat for the hammer arranged to intersect the axis of the disk.

4. In a frame for pneumatic riveting hammers, a frame for supporting the upper portion of a hammer casing, a rotating disk, a guide piece pivoted on the latter near

the periphery thereof and having a recess therein normally located in the axis of the disk to receive the lower end of said casing, and locking means for the 5 guide piece arranged concentric to the pivot thereof.

In testimony that I claim the foregoing as

my invention, I have signed my name in presence of two subscribing witnesses.

ANTON GJELSTAD.

Witnesses:

C. NORMAN,
C. FABRICIUS HANSEN.
